(57) **CLAIM**

The ornamental design for a food juicing attachment for a kitchen appliance, as shown and described.

DESCRIPTION

FIG. 1 is a perspective view of a food juicing attachment for a kitchen appliance, showing the new design.

FIG. 2 is a front view of the food juicing attachment of FIG. 1.

FIG. 3 is a back view of the food juicing attachment of FIG. 1.

FIG. 4 is a first side view of the food juicing attachment of FIG. 1.

FIG. 5 is a second side view of the food juicing attachment of FIG. 1.

FIG. 6 is a top view of the food juicing attachment of FIG. 1.

FIG. 7 is a bottom view of the food juicing attachment of FIG. 1; and,

FIG. 8 is a cross-sectional view of the food juicing attachment taken along line 8-8 of FIG. 7.

1 Claim, 5 Drawing Sheets
